GEORGE D. BEAUCHAMP, OF LOS ANGELES, CALIFORNIA

STRINGED MUSICAL INSTRUMENT

Application filed January 21, 1930. Serial No. 422,837.

This invention relates to stringed musical instruments embodying thin metallic resonators or diaphragms adapted to be tensioned against or connected with the strings in such a manner that the vibrations set up in the strings when the instrument is played will be substantially amplified and the volume of the instrument increased.

An object of my invention is to provide in 10 such an instrument an improved type of diaphragm so formed that a single large diaphragm may be employed in lieu of a plurality of smaller diaphragms. It will be understood that in instruments of the type 15 mentioned the size of the diaphragms influences the quality and volume of the tones produced by the instruments. That is to say, that diaphragms of the character generally used which are conical in form and are connected with the strings at their apexes become inefficient as amplifiers or resonators as their diameters are increased beyond certain limits. In case diaphragms of excessive diameter are employed the vibrations which 20 emanate from the strings and are distributed to the diaphragms at their axes are dissipated before they reach the peripheries of the diaphragms. It is, however, desirable to provide in an instrument of the character mentioned a single diaphragm in lieu of a plurality of diaphragms for the reason that a single diaphragm lends itself to a more economical and simple construction.

Accordingly this invention comprehends 35 the provision of an improved form of diaphragm of relatively large diameter as compared to diaphragms usually employed in such instruments. My improved diaphragm may be said to be generally of conical cross 40 section, but includes a plurality of smaller conical portions or expressions integral with the main cone but having their axes arranged at points intermediate the axis and the periphery of the diaphragm. In this type of construction the vibrations from the strings 45 are communicated to the apexes of the smaller conical portions at points nearer the periphery of the main cone than would be possible were the strings connected with the 50 apex of the main cone. Furthermore, there

being a plurality of the conical expressions the vibrations from the strings are communicated at a plurality of points, preferably concentric with respect to the axis of the main cone, thus insuring a uniform distribution 55 of the vibrations thruout the diaphragms.

This construction also provides clarity and quality of tone comparable with that obtained by the use of a plurality of separate 60 diaphragms.

Another object is to provide an improved body structure for mounting the composite diaphragm in operative relation with the 65 strings.

Other objects may appear in the description hereinafter following.

In the accompanying drawings I have shown a preferred form of my invention, in 70 which

Fig. 1 is a top plan view of an instrument embodying my improvements.

Fig. 2 is a transverse section of the same on line 2—2 of Fig. 1.

Fig. 3 is a fragmentary section of the instrument on line 3—3 of Fig. 2.

Fig. 4 is an enlarged sectional plan of a diaphragm and supporting means therefor on line 4—4 of Fig. 2.

Fig. 5 is a top plan view of a diaphragm. 80

Fig. 6 is a side elevation of the same.

The body of the instrument is preferably formed of thin sheet metal with the top 1 and bottom 2 substantially spaced apart and connected by a continuous side portion 3. 85 A neck 4 and a tail piece 5 are suitably secured to opposite ends of the body and serve to support a plurality of strings 6, 6 etc., in tension over the top 1. The top of the body has a depressed central portion 7 integrally formed therewith and provided with an inwardly turned flange 8 at the bottom, thus forming a shallow compartment 9 at the top of the instrument, in which is held a single 90 diaphragm 10.

The top 1 is counter-sunk at 11 at the upper side of the depression 7 so as to provide a seat for a plate 12 which closes the upper side of the compartment 9 and is attached to the body by means of screws or rivets 13. 100

The plate 12 has a central aperture 14 and a plurality of sets of apertures 15 therein thru which the tones of the instrument emanate. The diaphragm 10 is generally of conical cross section and has a peripheral flange 15 adapted to seat on the flange 8 of the body. One or more annular beads 16 may be formed internally of the flange 15 for rendering the diaphragm sufficiently flexible and more sensitive to vibrations than would be possible without the beads.

The diaphragm 10 is supported on the portion 7 at the top with its concave side downward and its convex side upward, and is formed with a plurality of conical portions 17, 17 etc., concentrically arranged about the axis thereof. The conical portions 17 intersect the main cone of the diaphragm 10 and are positioned with their axes intermediate the axis and the periphery of the main cone. A spider 18 is mounted on the diaphragm 10 and is provided with a plurality of arms 19, 19 etc., with terminal portions 20, 20 etc., formed thereon which are adapted to rest upon the apexes of the portions 17. I may provide apertures at the apexes of the portions 17 to receive teats as at 21, so that the spider 18 will be incapable of displacement from operative position on the diaphragm. I prefer to arrange the spider 18 with two of the arms 19, 19 in longitudinal alignment and the other at right angles thereto, as shown in Fig. 4, especially where three of the conical portions 17 are provided on the diaphragm. By this means I may groove the right angularly disposed arm 19 of the spider to receive a wooden bridge 22. Thus the spider 18 supports the bridge 22 in frictional engagement with the strings 6, as shown in Fig. 3, and the strings are tensioned over the bridge as usual.

It will be noted that the bridge 22 extends upwardly thru the central opening 14 in the plate 12 and I provide a guard 23 formed of flat strap metal which extends transversely over the strings 6 and the opening 14 and is bent downwardly at its ends and suitably secured to the plate 12. The guard 23 also serves as a hand rest for the operator when the instrument is being played.

From the foregoing description of my invention, considered with the illustrations of the drawing, it will be apparent that by communicating the vibrations from the strings 6 to the apexes of the conical portions 17 in the diaphragm 10, particularly at points outwardly of the axis of the diaphragm, the vibrations will more readily traverse the distances from the apexes of the smaller cones to the outer periphery of the main cone than they would from the axis to the periphery of the main cone, and substantially the same quality of tone will be provided in a single diaphragm which would otherwise be provided in a multiple diaphragm instrument.

The supporting portion 7 of the body has a large central aperture 24 therein so that vibrations set up in the strings and transmitted thru the diaphragm 10 are communicated thru the opening to the bottom 2 and thru actual contact with the portion 7 to the top 1 of the body. Thus maximum vibrational qualities are produced without interference or deadening of the vibrations.

What I claim is:

1. A stringed musical instrument including a body with strings held in tension thereon, a single metallic diaphragm mounted in said body, and having a plurality of portions at central points arranged to support said strings, for the purpose described. 75

2. A stringed musical instrument comprising a body having strings held thereon in tension, a diaphragm mounted in said body and provided with a plurality of conically formed portions, and means engaging corresponding points of said portions and also engaging said strings for the purpose described. 85

3. A stringed musical instrument comprising a body having strings held thereon in tension, a diaphragm having a plurality of cones formed thereon and having axes intermediate the axis and periphery of the diaphragm, and means intermediate the axes of said cones and said strings for communicating the vibrations from the strings to the diaphragm. 90

4. A stringed musical instrument including a body having strings adapted to be held in tension thereon, a unitary diaphragm formed of sheet metal supported at its periphery on said body and provided with a plurality of portions bent outwardly from its periphery, and means engaging said outwardly bent portions and said strings, for the purpose described. 100

5. A stringed musical instrument comprising a body having strings held in tension thereon, a metal diaphragm supported at its periphery on said body and provided with a plurality of portions bent outwardly from the plane of its periphery, and common means engaging corresponding points on said outwardly bent portions and engaging said strings, for the purpose described. 110

6. In a stringed musical instrument, a metal diaphragm having a peripheral supporting flange and a plurality of outwardly bent cones with axes concentric with the axis of the diaphragm. 120

7. In a stringed musical instrument, a diaphragm in the form of a shallow cone having a peripheral supporting portion and a plurality of conical portions intersecting the main cone and arranged with their axes concentric with the axis of the main cone. 125

8. A stringed musical instrument comprising a body having its top bent downwardly and inwardly to provide a support, a plate se- 130

cured to the top of said body, strings held in tension over said plate, a diaphragm held at its periphery on said support and having a plurality of cones bent outwardly from the plane of the periphery of said diaphragm, and common means engaging corresponding portions of said cones and said strings, for the purpose described.

9. A stringed musical instrument comprising a body having its top bent downwardly and inwardly to provide a support, a plate secured to the top of said body, strings held in tension over said plate, a diaphragm held at its periphery on said support and having a plurality of cones bent outwardly from the plane of the periphery of said diaphragm, and common means engaging corresponding portions of said cones and said strings, said means including a spider in contact with the diaphragm, and a bridge intermediate said spider and said strings, for the purpose described.

10. A stringed musical instrument comprising a body having its top bent downwardly and inwardly to provide a support, a plate secured to the top of said body, strings held in tension over said plate, a diaphragm held at its periphery on said support and having a plurality of cones bent outwardly from the plane of the periphery of said diaphragm, common means engaging corresponding portions of said cones and said strings, said means including a spider in contact with the diaphragm, a bridge intermediate said spider and said strings, said plate having an opening thru which said bridge extends, and a guard secured to said plate and overlying said strings.
